Primary Examiner — Mojtaba Tehrani(74) *Attorney, Agent, or Firm* — Distinct Patent Law;
Justin P. Miller(57) **CLAIM**

The ornamental design for a frame, as shown and described.

DESCRIPTION

FIG. 1 is a first perspective view of a frame showing the new design;

FIG. 2 is a right-side elevation view thereof;

FIG. 3 is a left-side elevation view thereof;

FIG. 4 is a front elevation view thereof;

FIG. 5 is a back elevation view thereof;

FIG. 6 is a top plan view thereof;

FIG. 7 is a bottom plan view thereof;

FIG. 8 is a second perspective view; and,

FIG. 9 is a third perspective view.

The broken lines in the drawings disclose unclaimed portions of the frame only and form no part of the claimed design.
